DIRECTIONAL ANTENNA

John J. Root, New York, N. Y.

Application May 5, 1950, Serial No. 160,349

3 Claims. (Cl. 250—33.51)

1

This invention relates to high frequency antennas for use in television and frequency modulation receivers.

To insure maximum efficiency of reception, it is essential that television receivers be equipped with a directive antenna which is of a size adapted to resonate approximately within the frequency range of reception. When a television receiver is located at some distance from the transmitter, it is usually necessary to employ an elaborate antenna having elements of adequate size to resonate at desired frequencies. At locations closer to the transmitter, simplified antennas may be used and it is seldom that an antenna can be dispensed with entirely.

In large cities, where television transmitters are located, the correspondingly large number of television receivers in a substantial number of instances are not adapted to be provided with the elaborate types of antenna heretofore known in the art. The location of large numbers of receivers in apartment houses makes it difficult to install outdoor antennas of the complicated type necessary to insure adequate reception. Furthermore, such antennas involve substantial costs, both in their manufacture and in their installation.

Antennas have been installed within the cabinet of the television receiver, but such antennas have been found to be inadequate in most instances. While it would be desirable to orient such antennas in order to improve reception, the movement of the cabinet to effect such orientation of the antenna is not feasible since the screen might be moved out of its normal viewing position.

Accordingly, an object of this invention is to provide an improved antenna for television reception which does not have to be mechanically rotated in order to obtain proper orientation, such orientation being obtained electrically by improved condenser means interconnecting the antenna elements.

Another object of this invention is to provide an antenna including crossed dipoles which are bridged by means of a slidable type variable condenser for effecting electrical orientation of the antenna in accordance with selected positions of a slidable element of the condenser.

Still another object of this invention is to provide a television antenna of the crossed dipole type in combination with a variable condenser for effectively rotating the antenna in space, the condenser forming direct mounting means for the dipoles.

2

A further object of this invention is to provide for use as a bridging means in an antenna of the crossed dipole type, a simple form of capacitor, which is inexpensive to manufacture, is easily operated and is efficient to a high degree in use.

Other objects of this invention will in part be obvious and in part hereinafter pointed out.

In the accompanying drawing, in which is shown an illustrative embodiment of the invention,

Fig. 1 is a perspective view of the upper portion of a television receiver cabinet, indicated in dot-dash lines and equipped with a built-in antenna embodying the invention.

Fig. 2 is a top plan view of the antenna.

Fig. 3 is an enlarged top plan view showing details of the condenser portion of the antenna, with parts thereof removed.

Fig. 4 is a sectional view taken on the line 4—4 of Fig. 3.

Fig. 5 is a sectional view taken on the line 5—5 of Fig. 3, and

Fig. 6 is a perspective view of the slidable member of the condenser, with a part thereof broken away.

The top of the television receiver cabinet is generally indicated at A, the antenna embodying the invention being generally indicated at 10, and illustrated as suitably mounted on the underside thereof.

The antenna 10 comprises dipole sections 11 and 12 forming one dipole and dipole sections 13 and 14 forming another dipole. As shown in Fig. 2, the dipoles are located in crossed relationship so that they are substantially in perpendicular relation to each other. The dipole sections 11 and 13 are bridged or interconnected at their outer ends by a member 15 which may be integral with sections 11 and 13. It has been found that such bridging increases the impedance match between the antenna and receiver input and further increases gain at low frequencies. The inner ends of sections 11 and 13 include angular terminal portions 16 and 17, respectively which are in alignment with each other, the opposite ends thereof being slightly spaced from each other. The dipole sections 12 and 14 are interconnected at their outer ends by a conductive member 18 which is substantially parallel to member 15. The inner ends of sections 12 and 14 are interconnected by a conductive member 19 which may be integral therewith and is substantially parallel to member 18. A conductive member 20 extends from the midpoint of member 18

45

50

55

to the midpoint of member 19, interconnecting members 18 and 19. The member 20 has been found to be effective in substantially increasing the antenna gain. The dipole sections and their interconnecting members may take the form of wire conductors of circular cross section and of suitable stiffness.

Means is provided for suitably arranging the dipoles relative to each other and to maintain the same in the desired relationship. Such means further serves to bridge the dipoles and to allow for adjusted electrical orientation of the antenna constituted by the dipoles. To this end, a variable condenser, generally designated as C, is provided. The same comprises a pair of similar rectangularly-shaped sheets 21 and 22 of suitable stiffness, such as vulcanized fiber or the like, which are disposed in overlying relation to each other. Mounted on the upper face of the sheet 22 are a pair of similar stator plates 23 and 24 of conductive material arranged in side-by-side, spaced relation to each other and which form the fixed conductor elements of the condenser C. The terminal portions 16 and 17 of dipole sections 11 and 13 are arranged in contacting relation with plates 23 and 24, respectively, as shown in Fig. 3.

The member 19 of dipole sections 12 and 14 is also arranged on sheet 22, being located in spaced relation to plates 23 and 24. A thin sheet of dielectric material 25 such as fish paper or the like is disposed over the upper faces of stator plates 23 and 24. A conductive plate 26 is slidably arranged for capacitive relation to stator plates 23 and 24 to form the movable element of condenser C. The plate 26 is arranged on the underside of an elongated slider strip 27 of suitable stiffness such as cardboard. The plate 26 includes a terminal lug 28 struck up from the body of the plate and projecting upwardly through an opening in slider strip 27. The supporting sheet 21 is formed with an elongated, rectangular slot 29 to accommodate terminal 28, upon slidable movement of slider 27. The movement of strip 27 is guided by a pair of spacer strips 30 and 31 located over the dipole end portions 16 and 17 and dipole member 19, respectively and having their upper faces contacting the inner surface of sheet 21. The strips 30 and 31 define therebetween a track for movement of slider 27, the limits of movement in opposite directions being established by contact of lug 28 as it contacts the opposite ends of slot 29.

The sheets 21 and 22, as well as the plates 23, 24 and 26, and the dipole sections are retained in their relative position by means of staples 32 passing through the superposed sheets as indicated. It is understood that fastening means other than staples may be used for securing the sheets and associated condenser elements in their desired relationship.

The strip 27, which is of such length that it may project beyond sheets 21 and 22, is formed on its outer end with an opening 33 for receiving the inturned end 34 at the inner end of manually operable rod 35. The rod 35 includes at its outer end a reversely turned portion 36 which is adapted to project from a suitable opening formed in cabinet A. The adjacent outer ends of rod 35 and portion 36 are provided with a knob 37 by which the strip 27 may be reciprocated in opposite directions.

Connection between the antenna 10 and the input of the television receiver is made through wires 38 and 39. Wire 38 is soldered to terminal

28 on plate 26 while wire 39 is soldered to member 20.

As shown in Fig. 5, the plate 26 on slider strip 27 is of such dimension as to substantially overlie and cover stator plate 24, when the strip is in its retracted position. Similarly, when strip is moved by means of knob 37 to its extreme forward position, plate 26 will substantially cover and overlie stator plate 23. Thus, in one extreme position of slider 27, the dipole sections 11 and 12 are bridged capacitatively by plate 26 and plate 23, while in the other and opposite extreme position, dipole sections 13 and 14 are bridged capacitatively by plate 26 and plate 24. Accordingly, the antenna 10 may be electrically oriented without mechanical movement to opposite directions.

Upon movement of the slider 27 to positions intermediate of the extreme positions thereof, plate 26 will be placed in overlapping relationship to stator plates 23 and 24, thus electrically orienting the antenna to adjusted directions intermediate the extreme opposite directions previously referred to.

Such condenser C, while extremely simple in construction, is effective in providing for electrical orientation of the antenna, since the directional dipoles as arranged accommodate signals received from any direction. The signals are then selected through slidable movement of the variable condenser C so as to effectively orient the antenna in space. The conductor members 15 and 18 which connect the free ends of the dipole sections appear to have an inductive effect which compensates for the shortness of the dipoles.

While the condenser C effectively functions as means for electrically rotating or orienting the dipoles, the condenser in addition probably acts to properly phase incoming signals, although such incoming signals may reach the antenna out of phase. In addition, the condenser appears to provide a tuning action which increases gain.

It is understood that the condenser elements 23, 24 and 26 may take the form of electrically conductive coatings applied directly to the appropriate dielectric members.

The invention disclosed herein is of the type shown in applicant's co-pending application Serial No. 123,022, filed October 22, 1949, Patent No. 2,552,816, granted May 15, 1951, and constitutes an improvement thereover.

It is apparent that the dipoles herein disclosed are effectively mounted in their desired relationship by being directly secured to the variable condenser C which is effective to rotate the dipoles in space electrically, thus providing an integral structure which may be mounted as a unit on the cabinet of the television receiver.

The nature and construction of the condenser C, as well as the manner of its association with the dipoles, provides a highly economical antenna system which is effective in attaining the objects of the invention as hereinabove described.

What is claimed is:

1. A television antenna system comprising a pair of dipoles crossed so as to be effective in substantially mutually perpendicular directions, variable condenser means comprising two stator plates respectively connected to a pair of inner ends of said dipoles and a slidable plate in capacitative relationship to said stator plates for electrically rotating the directional characteristics of said dipoles, a first bridging element between the two adjacent outer ends of said di-

poles, a second bridging element between the other pair of inner ends of said dipoles and a connecting element between said first and second bridging elements and substantially perpendicular thereto.

2. A variable condenser for use with television antennas comprising a pair of superposed supporting sheets, a pair of conductive condenser elements disposed in end-to-end, spaced relation between said sheets, a dielectric member disposed over said condenser elements, a slidable supporting member disposed between said sheets, a conductive condenser element mounted on said slid-
able member for capacitative relation to said pair of condenser elements, a lug on said slidable member, one of said sheets being formed with a longitudinal slot within which said lug rides for guiding the movement of said slidable member, and means for retaining said sheets and condenser elements in relation to each other.

3. A television antenna system comprising a pair of dipoles crossed so as to be effective in substantially mutually perpendicular directions, each of said dipoles including a section having an inner terminal end adjacent one another, the outer ends of said sections being connected together, each of said dipoles including another section having their respective opposite ends connected to each other, means for mounting adjacent portions of said dipoles comprising a pair of superposed supporting members, a pair of condenser elements arranged between said supporting members in spaced relationship, each of said condenser elements being disposed in con-

tact with one of the terminal ends of said first mentioned dipole sections, a slidable condenser element arranged for movement with respect to said pair of condenser elements and in capacitive relation thereto, the inner ends of said second mentioned dipole sections being connected and received between said supporting members and in spaced relation to said condenser elements, means for securing said supporting sheets together whereby to retain said condenser elements and said dipoles in proper relation to each other, an output terminal on said slidable condenser element and an output terminal on said second mentioned dipole section, the dipoles being adapted to be effectively rotated in space by movement of said slidable condenser element relative to said pair of condenser elements.
